US00D993545S

(12) **United States Design Patent** (10) **Patent No.:** **US D993,545 S**
(45) **Date of Patent:** **** Jul. 25, 2023**

(54) **LICK PLATE FOR PETS**

(71) Applicant: **Guangzhou Jinyu Outdoor Products Co., Ltd.**, Guangzhou (CN)

(72) Inventor: **Zhenwang He**, Guangzhou (CN)

(73) Assignee: **GUANGZHOU JINYU OUTDOOR PRODUCTS CO., LTD.**, Guangdong Province (CN)

(**) Term: **15 Years**

(21) Appl. No.: **29/854,337**

(22) Filed: **Sep. 23, 2022**

(51) **LOC (14) Cl.** **30-03**

(52) **U.S. Cl.**

USPC **D30/121**

(58) **Field of Classification Search**

(57) **CLAIM**

The ornamental design for a lick plate for pets, as shown and described.

DESCRIPTION

FIG. 1 is a front and top perspective view of a lick plate for pets, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the lick plate for pets that form no part of the claimed design.

1 Claim, 8 Drawing Sheets
